UNITED STATES PATENT OFFICE.

GEORGE HENRY WHEARY, OF RACINE, WISCONSIN.

INSIDE PAD FOR TRUNKS.

1,093,226.

Specification of Letters Patent. Patented Apr. 14, 1914.

Application filed January 30, 1914. Serial No. 815,333.

To all whom it may concern:

Be it known that I, GEORGE H. WHEARY, a citizen of the United States, and resident of Racine, in the county of Racine and State of Wisconsin, have invented new and useful Improvements in Inside Pads for Trunks, of which the following is a description, reference being had to the accompanying drawings, which are a part of this specification.

10 This invention relates to improvements in inside pads for trunks and more particularly to pads for retaining garments in suspended position in the wardrobe section of a wardrobe trunk.

15 In wardrobe trunks of the better type as now constructed the trunk body is divided vertically medially into two sections which are hinged together and are adapted to swing horizontally to open position. One of these 20 sections is usually provided with draws and other compartments and the other section, called the wardrobe section, is usually provided with garment hanger tracks upon which garment hangers are slidably mounted. The tracks are usually of the extensible type to permit the hangers to be slid outwardly on the tracks while in suspended positions. Garments are suspended by and folded over the hangers and in order to permit them to be freely removed from the trunk section the upper end of the section is open and is provided with a cover which may be swung upwardly to open position. In trunks of this type it is necessary to provide means for engaging the hangers and garments to securely hold them in place and prevent their accidental disarrangement during transportation and without injury to the garments.

25 It is one of the objects of this invention to provide the wardrobe section of a wardrobe trunk with means for firmly and yieldingly holding the hangers and garments carried thereby in position with the said section.

30 A further object of the invention is to provide an inside pad for trunks which is of simple construction and is well adapted for the purpose desired.

With the above and other objects in view, 35 the invention consists of the improved inside pad for trunks and its parts and combinations as set forth in the claims, and all equivalents thereof.

In the accompanying drawing in which 40 the same reference characters indicate the same parts in all of the views: Figure 1 is a

front view of the wardrobe section of the trunk provided with the improved inside pad, a portion of the wardrobe section front door being broken away and a part of the drawer section being indicated by dotted lines: Fig. 2 is a vertical sectional view thereof taken on line 2--2 of Fig. 1. Fig. 3 is a similar view of the upper portion of the section with the cover shown in open position and one of the extensible rails swung outwardly; and Fig. 4 is a similar view thereof provided with a modified form of pad.

Referring to the drawing the numeral 8 indicates the trunk body generally, which is divided vertically to form a body section 9 and a wardrobe section 10 hinged thereto and arranged to be swung horizontally to open position. The upper end of the wardrobe section is open and is provided with a cover 11 hinged to the rear wall thereof which is adapted to close the end of said section. This cover is provided with side and rear depending flanges 12 which overlap the upper end portions of the wardrobe section and enter the recessed portions 13 thereof. The front open side of the wardrobe section is closed by a door 14 which carries a shoe box 15 and another container 16, both of which form part of the door and are positioned within the wardrobe section and near the bottom portion thereof.

Garment hanger tracks 17 mounted in the upper portion of the wardrobe section are provided with extensions 18 hinged to their outer ends which are adapted to be swung horizontally outwardly to extended positions. Garment hangers 19 slidably and removably mounted on the tracks are adapted to support and have garments folded thereover.

A yielding pad 20 interposed between the cover and the garment hangers is of greater thickness than the space between the cover 10 and the upper portions of the garment hangers so that said portions of the garments folded thereon will embed into the pad when the trunk cover is in closed position.

In the modified form shown in Fig. 4 the pad 20' is not attached to the trunk cover but in other respects is similar to the first mentioned pad.

By means of the pad the garment hangers 11 and the garments folded thereon are held firmly in position without the liability of

the garments being injured by rubbing against the holding means.

From the foregoing description it will be seen that the inside pad is of very simple construction and is well adapted for the purpose described.

What I claim as my invention is:

1. A wardrobe trunk, comprising a trunk body divided vertically into two sections which are hinged together, one of said sections having an upper open end, a cover hinged to the trunk body for closing said open end, garment hanger tracks mounted in the upper portion of the open ended section, garment hangers slidably mounted on said tracks, and a pad interposed between the cover and the garment hangers and into which the garment hangers are adapted to embed when the cover is in closed position.
2. A wardrobe trunk, comprising a trunk body divided vertically into two sections which are hinged together, one of said sections having an upper open end, a cover hinged to the trunk body for closing said open end, garment hanger tracks mounted within the upper portion of the open ended section on the opposite side walls of said section, garment hangers extending transversely across the open ended section and slidably mounted on said tracks, and a pad interposed between the cover and the tracks and engaging the portions of the hangers between the tracks, the said pad being of greater thickness than the distance between the cover and the upper edge portions of the garment hangers to cause the said hangers to embed into the pad when the cover is closed.
3. A wardrobe trunk, comprising a trunk body divided vertically into two sections which are hinged together, one of said sec-

tions having an upper open end, a cover hinged to the trunk body for closing said open end, garment hanger tracks mounted within the upper portion of the open ended section on the opposite side walls of said section, garment hangers extending transversely across the open ended section and slidably mounted on said tracks and a loose pad interposed between the cover and the tracks and engaging the portions of the hangers between the tracks, the said pad being of greater thickness than the distance between the cover and the upper edge portions of the garment hangers to cause the said hangers to embed into the pad when the cover is closed.

4. A wardrobe trunk, comprising a trunk body divided vertically into two sections which are hinged together, one of said sections having an upper open end, a cover hinged to the trunk body for closing said open end, garment hanger tracks mounted within the upper portion of the open ended section on the opposite side walls of said section, garment hangers extending transversely across the open ended section and slidably mounted on said tracks, and a pad removably positioned between the cover and the garment hangers, the said pad being of greater thickness than the space between the cover and the upper edge portions of the garment hangers to cause the hangers or clothes draped thereon to embed into the pad.

In testimony whereof, I affix my signature, in presence of two witnesses.

GEORGE HENRY WHEARY.

Witnesses:

GEORGE BEMISH,
ANNA M. NELSON.
